UNITED STATES PATENT OFFICE.

CARL E. BROWN, OF COLUMBUS, OHIO.

ELECTRIC TRACKER MECHANISM.

Application filed October 11, 1923. Serial No. 667,814.

My invention relates to electric tracker mechanism for player pianos, or other like instruments, and more particularly to control thereof, in such a way as to shift from one kind of music to another from a point of remote control.

My invention also relates to electrically operated players, and to a mode of controlling not only the movement of a perforated sheet across a tracker bar, but also in shutting on and off the electric current from these perforated rolls which are not in use.

In the moving picture theatre there is a decided need for control of the music by the picture machine operator, in order to provide music of the correct character for the different scenes and episodes of the picture. My invention is directed toward the provision of such a means, and also the use of the usual perforated music roll in the selection of electric circuits to energize electromagnets setting into operation the several notes of the piano or organ. I wish to note here that by use of the term piano in this specification, I wish to include organs and other like automatic musical instruments.

In the use of slotted rolls for exposing electric contacts, and shifting from one set of music sheets to another, it is necessary to shut off the current from the tracker bar, in shifting from one player mechanism to another, or else certain of the notes, as exposed through the idle player mechanism may block the operation of these notes by another, or cause discordant notes to be sounded. My invention as noted provides a mechanism for accomplishing this, said mechanism operating at the same time and from a remote point, the clutch mechanism by means of which the paper feed is controlled.

These objects and advantages I accomplish by that certain construction and arrangement of parts to be hereinafter more specifically pointed out and claimed.

In the drawings:

Figure 1 is a side elevation showing two units of a selective automatic player.

Figure 2 is a plan view of the parts shown in Figure 1.

Figure 3 is a detail side elevation on a larger scale of a tracker bar, and the controlling mechanism.

Figure 4 is a detail of the operating mechanism for the sliding sleeve clutch.

Referring to the drawings, which are in-

tended as illustrative, rather than as by dimension and detail, showing only possible construction, I show frame parts, generally as 1, and sheets of perforated music paper 2. It will be understood that these music sheets are preferably formed in a continuous band, and each band arranged to render music of one selected type, such as martial, sentimental, gay, and the like. There may be as many different player units as desired. Extending along in the frame outside of the tracker compartments is a drive shaft 3, which is always in motion, the drive shaft having a series of keyed sliding sleeves 4, 4, 70 one for each player mechanism, these sleeves having pinions 5 fixed thereon. An electromagnet 6, is provided for each sleeve operation, these magnets being controlled from a selective switch at a remote point, say a 75 moving picture booth in a moving picture theatre.

The magnets have armatures 7, sliding on guide pins 8, and having small brackets 9 secured to the outer faces thereof. These 80 brackets engage over flanges 10 on the sleeves, so that the sleeves are pulled in this instance, to the left, when the magnets are operated. The sleeves also have arms 11 thereon, which extend parallel to the shaft 85 3, said arms being equipped with fingers 12, which as will be noted trip the tracker contact brushes.

Referring now to the playing mechanism, it will be noted that I show several tracker bars 13, in which are set sufficient contact pins 14, at least for each note in the piano.

Rolls of perforated music sheets are slipped into sockets mounted in the frame supporting the tracker mechanisms. The front ends of the sheets are passed over guide rolls, then over the tracker bars and by raising the weighted pressure rolls 15 in their axial slots in the frame passed between them and the drive rolls 16 which are preferably faced with rubber. The perforated music sheets, passing from the drive rolls, may be confined in any suitable space below the drive rollers until it is desired to rewind them on their respective rollers. The particular construction of the music rolls or the manner in which they are mounted are not within the scope of this invention, my device providing a simple method of insertion over the tracker bars and adjustment within the driving rolls. The driving rolls 16 have spindles extending through the frame where

they are equipped with gears 17. These gears 17 lie alongside of the shaft 3, and the energizing of any magnet pulls pinion 5 to a position of mesh with the adjacent gear 17.

- 5 The brush as herewith illustrated has a body 20, mounted on a rock shaft 21. The body forms a casing for a long brush, the length of the tracker bar, and formed of a large number of fine copper or brass wires 10 22, having the ends cut to form a flat contact over the tracker. A long weight 23, mounted on a part of the body of the brush by means of a plate 24, rests on the wires of the brush, and keeps them against the tracker. The 15 rock shaft has depending tongues 25, which lie in the path of the fingers 12, of the clutch device. Thus the action of the electro-magnets in drawing the clutch sleeves into meshing position to drive the sheet music feed 20 roll, will also release the brush for the particular tracker, permitting it to fall into contact position. A spring 25^a secured to each finger, acts as a return against the action of the magnets, thereby restoring each 25 magnet to non-energized position of its armature, the clutches to non-engaging relation, and the brushes to position swung by means of their rock shafts out of contact with their trackers.
- 30 It will be noted that the remote control of this device can be very simply arranged, throwing the selected magnet for the kind of music desired into closed circuit and opening all other magnet circuits, by a simple selective switch.

Having thus described my invention, what I claim as new and desire to secure by Letters Patent, is:—

1. An electrical regulating device for 40 musical instruments, employing perforated roll music sheets, comprising a series of independent tracker bars, and paper feeding devices, and a series of electric contact brushes, one for each tracker bar, a common 45 driving element for the paper feeding devices, clutches intermediate the driving ele-

ment, and the several feeding devices, brush contact inhibiting means and said clutches operatively connected therewith.

2. An electrical regulating device for 50 musical instruments, employing perforated roll music sheets, comprising a series of independent tracker bars, and paper feeding devices, and a series of electric contact brushes, one for each tracker bar, a common 55 driving element for the paper feeding devices, clutches intermediate the driving element and the several feeding devices, brush contact inhibiting means and said clutches operatively connected therewith, and operating mechanism for said clutches, having a 60 remote control.

3. A regulating device for musical instruments, employing perforated roll music sheets, comprising a series of independently 65 inhibitive trackers and a series of independently inhibitive brushes for said trackers, paper feed device having a driving gear therefor, one for each tracker, a driven shaft, a series of sliding sleeves on the shaft having 70 gears to mesh with said feed device gears, and individual electrical operating means for the sleeves whereby any selected one of the feed devices can be operated.

4. A regulating device for musical instruments, employing perforated roll music sheets comprising a series of independently inhibitive trackers and a series of independently inhibitive brushes for said trackers, paper feed device having a driving gear 80 therefor, one for each tracker, a driven shaft, a series of sliding sleeves on the shaft having gears to mesh with said feed device gears, and individual electrical operating means for the sleeves whereby any selected one of the feed devices can be operated, said 85 brushes being rockable to and from contact position, and means on the sleeves for rocking the brushes into contact when the sleeves are drawn toward gear meshing position.

CARL E. BROWN.
